US00D991838S

(12) **United States Design Patent** (10) **Patent No.:** **US D991,838 S**
Yang (45) **Date of Patent:** **** Jul. 11, 2023**

(54) **FRAME FOR BICYCLE OR ELECTRIC BICYCLE**

(71) Applicant: **Shenzhen Sailvan Network Technology Co., Ltd.**, Guangdong (CN)

(72) Inventor: **Guoqing Yang**, Guangdong (CN)

(73) Assignee: **Shenzhen Sailvan Network Technology Co., Ltd.**, Shenzhen (CN)

(**) Term: **15 Years**

(21) Appl. No.: **29/800,178**

(22) Filed: **Jul. 19, 2021**

(51) **LOC (14) Cl.** **12-11**

(52) **U.S. Cl.**

USPC **D12/111**

CLAIM

The ornamental design for a frame for bicycle or electric bicycle, as shown and described.

DESCRIPTION

FIG. 1 is a top, front and right side perspective view of a frame for bicycle or electric bicycle showing my new design;

FIG. 2 is a bottom, rear and left side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

1 Claim, 8 Drawing Sheets
